UNITED STATES PATENT OFFICE.

BENJAMIN F. PIERCE, OF GLENWOOD, IOWA.

VETERINARY OPERATING TABLE.

Application filed January 3, 1927. Serial No. 158,747.

The invention relates to an operating table and more especially to the class of veterinary surgical or operating tables for animals.

The primary object of the invention is 5 the provision of a table of this character, wherein the body thereof is of novel form so that the animal can be conveniently clamped or held in the desired position for 10 operating purposes, especially for vaccination, the table being of novel form, so that when an animal is placed thereon it will be firmly held, without any possibility of such animal working loose.

Another object of the invention is the provision of a table of this character, wherein the fastening elements for holding the animal are mounted in a novel manner so that they can be adjusted to suit the fancy of the user of the table and to firmly hold the animal when upon the table.

A further object of the invention is the provision of a table of this character, wherein the same is readily portable and can be folded or knocked down when not in use, 25 so as to occupy the least possible space and when set up for use will be firm.

A still further object of the invention is the provision of a table of this character which is comparatively simple in construction, 30 thoroughly reliable and efficient in its purposes, strong, durable, susceptible of wide range of adjustment and inexpensive to manufacture and install.

With these and other objects in view, the 35 invention consists in the features of construction, combination and arrangement of parts, as will be hereinafter more fully described, illustrated in the accompanying drawings, showing the preferred embodiments of the invention, and pointed out in the claims hereunto appended.

In the accompanying drawings:

Figure 1 is a top plan view of a table constructed in accordance with the invention.

45 Figure 2 is a side elevation, showing one end portion of the table broken away.

Figure 3 is a sectional view on the line 3—3 of Figure 1 looking in the direction of the arrow.

50 Similar reference characters indicate corresponding parts throughout the several views in the drawings.

Referring to the drawings in detail, the table generally includes a bed A and supporting legs B, the details of which will be hereinafter more fully described.

The bed A, is preferably made from wood, although the same may be made from any other suitable material and is of any required size, in this instance being of rectangular shape, but it may be of other shapes if found expedient. The legs B each comprise cross limbs 5 bolted or otherwise secured at their crossing points and at their upper ends carry a cross sill 6 the same being bolted or otherwise secured to said limbs. Mounted on the cross sill at one face thereof are hinges 7 which are likewise mounted upon the underface of the bed A, so that said cross legs B can be folded inwardly against 70 the underface of the bed, when the table is not in use. The cross limbs 5 carry a cross brace 8 having centrally loosely connected thereto an elongated hook 9 which is removably engaged in an eye 10 depending 75 from the underside of the bed A and this hook 9 when engaged in the eye 10 will hold the legs B in supporting position for the bed elevated relative to a foundation.

Removably fitted in the bed A at the corners thereof are upwardly divergent stanchions or posts 11, which serve as guards for the ends of the table, each stanchion or post 11 being removably fitted in an opening 12 formed in the bed A of the table.

Arranged transversely on the bed A centrally thereof is a series of spaced slate 13, the outer ones of which are of less width than the remaining intermediate slats and the same are made fast to the top of the bed A or integrally formed therewith as may be desired. The slats 13, in transverse section are of semi-oval shape. The slats 13 project above the upper face of the bed A and provide means for supporting the animal's body above the bed. The length of the slats 13 is less than the width of the bed A and said slats 13 terminate adjacent the side edges of said bed.

Arranged at one side of the bed A, between the stanchions or posts 11 on such side, and rising from said bed is a head rail or board 14 which constitutes a guide and an abutment for the body of an animal when placed upon the table, which animal rests upon the slats 13, preferably upon its side, although the posture of the animal can be altered or changed as required.

Suitably mounted in the bed A between the slats 13 medially relative thereto is a series of elongated guide yokes 15, each being of substantially inverted U-shape and

being bolted or otherwise fastened securely in the bed A. The slats 13 extend above the level of the yokes 15, so that the animal lying on the table will not be injured by the yokes 15. Slidably engaged with these yokes 15 are the inner ring ends 16 of retaining straps or members 17 having outer chain terminals 18, a selective link of each being designed for detachable fastening 10 with a pivotally mounted lever-like latch 19.

The bed A carries at one longitudinal edge a pair of lever-like latches 20, while at the opposite longitudinal edge is a series of the lever-like latches 19. The latches 20, as well 15 as the latches 19 designed to adjustably secure the retaining members 17 when properly adjusted to brace the body of the animal upon the bed to firmly hold the animal while thereon. When the retaining members 17 20 are swung towards the latches 19 these latter adjustably secure the members 17 in position, and when certain of the retaining members 17 are swung towards the latches 20, these latter adjustably secure the retaining members 17 in position.

Mounted on the stanchions or posts 11 are lever-like latches 21 with which are detachably engaged retaining elements 22, these carrying hook terminals 23 and being adapted to hold and secure the legs of an animal when placed upon the table for operating purposes.

In the use of the table when set up, the body of the animal is placed upon the bed A, to rest upon the slats 13, and thereupon, the retaining members 17 are chained over the body of the animal and secured in their adjusted position by the latches 19, while the legs of the animal are fastened by the retaining elements 22 as will be clearly obvious.

From the foregoing it is thought that the construction and manner of use of the table will be clearly understood and therefore a more extended explanation has been omitted.

What is claimed is:—

1. A table for the purpose set forth comprising a bed, legs for supporting it, an abutment at one side of the upper face of the bed, a plurality of spaced displaceable and adjustable animal retaining members slidably connected to the upper face of the bed, and means extended from said side of the bed for detachably securing said retaining members in animal retaining position.

2. A table of the character described comprising a bed, supporting means therefor, spaced transversely extending slats secured to the upper face of the bed, a plurality of 60 spaced displaceable and adjustable retaining members slidably connected with the bed between said slats, an abutment at one side of the bed adjacent one end of said slats, and means extended from said side of the

bed for detachably securing said retaining members in animal retaining position.

3. A table for the purpose set forth comprising a bed, legs for supporting it, an abutment at one side of the upper face of the bed, a plurality of spaced displaceable and adjustable animal retaining members slidably connected to the upper face of the bed, means extended from said side of the bed for detachably securing said retaining members in animal retaining position, an outwardly inclined, upstanding stanchion mounted at each corner of the bed and adjacent said slats, and means carried by each of said stanchions for detachably connecting the leg of an animal therewith.

4. A table of the character described comprising a bed, supporting means therefor, spaced transversely extending slats secured to the upper face of the bed, a plurality of spaced displaceable and adjustable retaining members slidably connected with the bed between said slats, an abutment at one side of the bed adjacent one end of said slats, means extended from said side of the bed for detachably securing said retaining members in animal retaining position, an upstanding stanchion connected to said bed at each corner thereof and adjacent said slats, and means carried by each of the stanchions for detachably securing the leg of an animal thereto.

5. A table for the purpose set forth comprising a bed, supporting means therefor, an abutment at one side of the upper face of the bed, spaced transversely extending slats connected with the upper face of the bed, yoke-shaped guides positioned between and spaced from said slats, displaceable and adjustable retaining members slidably connected to said guides, and means projecting from said side of the bed for detachably securing said members in animal retaining position.

6. A table for the purpose set forth comprising a bed, supporting means therefor, an abutment at one side of the upper face of the bed, spaced transversely extending slats connected with the upper face of the bed, yoke-shaped guides positioned between and spaced from said slats, displaceable and adjustable retaining members slidably connected to said guides, means projecting from said side of the bed for detachably securing said members in animal retaining position, upstanding and outwardly inclined stanchions connected with the bed at the corners thereof and adjacent said slats, and means carried by the stanchions for detachably connecting the leg of an animal therewith.

In testimony whereof, I affix my signature hereto.

BENJAMIN F. X PIERCE.
